(57) **CLAIM**

The ornamental design for a portion of a vehicle stereo receiver including a wireless charging pad, as shown and described.

DESCRIPTION

FIG. 1 is a perspective view of a portion of a vehicle stereo receiver including a wireless charging pad, showing my new design;

FIG. 2 is a front view of the vehicle stereo receiver shown in FIG. 1;

FIG. 3 is a rear view of the vehicle stereo receiver shown in FIG. 1;

FIG. 4 is a left side view of the vehicle stereo receiver shown in FIG. 1;

FIG. 5 is a right side view of the vehicle stereo receiver shown in FIG. 1;

FIG. 6 is a top view of the vehicle stereo receiver shown in FIG. 1;

FIG. 7 is a bottom view of the vehicle stereo receiver shown in FIG. 1;

FIG. 8 is a perspective view like that of FIG. 1 and illustrates the vehicle stereo receiver in use charging an electronic device on the wireless charging pad;

FIG. 9 is a perspective view of the vehicle stereo receiver shown in FIG. 1 with the wireless charging pad in a stored position within the vehicle stereo receiver; and,

FIGS. 10 through 12 are right side views illustrating movement of the wireless charging pad from the extracted position (FIG. 10), to an intermediate position (FIG. 11), and finally into the stored position (FIG. 12) within the vehicle stereo receiver.

The broken lines in FIGS. 1-12 illustrate unclaimed subject matter and do not form any part of the claimed design.
